FEEDING MECHANISM FOR SEWING MACHINES

Andrew B. Clayton, Silver Bay, N. J., assignor to
The Singer Manufacturing Company, Elizabeth,
N. J., a corporation of New Jersey

Application October 18, 1947, Serial No. 780,727

5 Claims. (Cl. 112—212)

1

This invention relates to feeding mechanisms for sewing machines and more particularly to a four-motioned upper feeding mechanism having a work-feeding foot engaging the upper face of the work and having, in conjunction therewith, a presser-foot which holds the work during the return stroke of the work-feeding foot. This type of feeding mechanism also usually includes means for alternately raising and lowering the presser-foot and the feeding-foot so that the presser-foot is lifted free of the work during the feeding stroke of the feeding-foot but holds the work during the return movement of the feeding-foot.

Feeding mechanisms of this nature may be used alone but, as shown in this application, are also used in conjunction with a lower feeding mechanism having a four-motioned feed-dog engaging the lower face of the work.

The primary object of this invention is to provide improved feeding and presser-foot lifting mechanisms which are devoid of harsh motions, and which will operate more quietly, with less vibration, and at higher speeds than those heretofore provided.

This has been accomplished by the provision of improved driving means for the feed and presser-lifting mechanisms which eliminates certain oscillatory elements of prior constructions and substitutes therefor rotary elements driven from the arm-shaft of the machine through relatively short and compact torsion-free driving connections.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a rear elevation of a sewing machine embodying the present invention.

Fig. 2 is a front end view of the machine shown in Fig. 1.

Fig. 3 is a sectional view taken substantially on the line 3—3 of Fig. 2.

Fig. 4 is a detail sectional view taken substantially on the line 4—4 of Fig. 2.

Fig. 5 is a detail sectional view taken substantially along the line 5—5 of Fig. 2.

Fig. 6 is a diagrammatic view illustrating, in full and dotted lines, the action of the means for

2

effecting the feed and return movements of the feeding-foot.

Fig. 7 is a diagrammatic view illustrating, in full and dotted lines, the action of the means for alternately lifting and lowering the presser-foot and the feeding-foot.

Referring more specifically to the drawings, the invention is disclosed as embodied in a sewing machine having a frame comprising a base 1 having a horizontally disposed work-supporting plate 2, a standard 3, and an overhanging bracket-arm 4 terminating in a hollow bracket-arm head 5. Journaled lengthwise within the bracket-arm is a main shaft 6 carrying, at its rear end, a combined belt- and hand-wheel 7 by means of which the shaft is rotated from any suitable source of power. Reciprocably mounted in bearings in the bracket-arm head is a needle-bar 8 carrying, at its lower end, an eye-pointed thread-carrying needle 9. The needle-bar is reciprocated by a crank-disk 10, secured to the shaft 6, through the medium of link 11 having its upper end connected to a crank-pin 12, carried by the crank-disk 10, and its lower end connected to a collar 13 clamped to the needle-bar.

Cooperating with the needle 9, in the formation of stitches, is a chain-stitch looper L forming a part of a looper mechanism designated generally as 14, in Fig. 2. The machine also includes a conventional lower four-motioned feed mechanism comprising a feed-dog 15 secured upon a feed-bar 16 adapted to be given endwise feed and return movements by mechanism designated generally as 17, and vertical movements by means designated generally as 18. The feed-dog 15 operates through a slot 19 formed in a throat-plate 20, fitted into the work-supporting plate 2.

Reciprocably mounted in the bracket-arm head 5, parallel to the needle-bar 8, is a presser-bar 21 which is depressed by a coil spring 22 and carries, at its lower end, a presser-foot 23. Secured to the presser-bar, by a screw 24 (Fig. 2), is a collar 25 having a rearwardly extending arm 26, the squared free end 26' of which tracks a guideway 27, formed in the machine frame, to prevent turning of the presser-bar about its longitudinal axis. The presser-bar, and the presser-foot carried thereby, may be lifted in opposition to the spring 22 by means of a treadle-actuated-lever 28 fulcrumed, at 28', on the bracket-arm. The forward end of the lever 28 embraces a stud 29 which projects rearwardly from the upper end of a vertically disposed bar 30, slidingly mounted in a bracket 31 secured to the rear side of the bracket-arm head (Fig. 4). At its lower end, the bar 30

carries an inwardly projecting arm 32 which underlies and engages the underside of the arm 26 carried by the presser-bar.

The improved feeding mechanism, which forms the subject of this invention, comprises a vertically disposed feed-bar 33, the upper end of which is fulcrumed, at 34, to one arm 35^a of a three-armed lever 35, hereinafter to be described. At its lower end the feed-bar carries a work-feeding foot 36 which, during its feeding stroke, bears upon the upper face of the work overlying the work-supporting plate 2 and throat-plate 20. Oscillatory, or feed and return, movements are transmitted to the feed-bar 33 and the feeding-foot carried thereby, from the rotary main shaft 6, by improved means now to be described.

Journalized in a bearing 37, provided by the bracket-arm 4 and bracket-arm head 5, adjacent and parallel to the rotary main shaft 6, is a feed actuating shaft 38 which is rotated from the main shaft, and synchronously therewith, (Fig. 3) through the medium of a one-to-one rotary driving connection, preferably, but not necessarily, comprising a driving gear 39 secured upon the main shaft 6 and a complementary driven gear 40 secured upon the shaft 38.

Formed integrally with the shaft 38, adjacent its forward end, is a feed drive eccentric 41 (Fig. 3) which is embraced by the cylindrical end 42^a of a pitman 42. The other end 42^b of the pitman is pivotally connected, at 43, to a segmental rock-arm 44 journaled, at 45, in the bracket-arm head 5. Thus, rotation of the main shaft 6 effects oscillation of the rock-arm 44 through relatively short and compact torsion-free driving connections.

Connected to the arm 44, (Fig. 5) by a stud 46^a having a slide-block 46^b adjustably mounted in an undercut slideway 46^a in the arm, is the upper end of a link 46. The lower end of this link is pivotally connected, at 47, to the outer end of a rock-arm 48 secured to the forward end of a rock-shaft 49 journaled in the bracket-arm head. Also secured to the rock-shaft 49, as by a pinch clamp 50, is a depending rock-arm 51 to the lower end of which is pivotally connected, at 52, one end of a horizontally arranged link 53 which has its other end pivotally connected, at 54, to the feed-bar 33. The rock-arm 48, rock-shaft 49 and rock-arm 51 constitute, in effect, a bell-crank lever but, because of the pinch clamp 50, permit relative angular adjustment between the two arms and thereby back and forth adjustment of the feed-bar. From the foregoing, it will be understood that rotation of the main shaft 6 effects back and forth, or feed and return, movements of the feed-bar 33 and the feeding-foot 36 carried thereby, the amplitude of such movements depending upon the point of connection between the link 46 and the rock-arm 44. When the stud 46^a is adjusted to a position where it is coaxial with the fulcrum 45 of the rock-arm 44, the feed and return movements transmitted to the feed-bar are reduced to zero.

The feed-bar 33 is guided in its feed and return movements and held against inward deflection by the contact of its inner surface with the flat forward face 5^x of the bracket-arm head (Fig. 2). Outward deflection of the bar is prevented by its contact with the inner face of a stepped plate 98 secured to the bracket-arm head by a screw 99.

Up and down movements are transmitted to the pressure-bar 21 and to the feed-bar 33 and the feeding-foot carried thereby, in timed re-

lation with the feed and return movements of the feed-bar, by means now to be described. Secured upon a reduced outer end portion 38^a of the shaft 38, (Fig. 3) by screws 55, is the hub 56 of an eccentric 57 which is surrounded by the sleeve end 58^a of a pitman 58. The other end of this pitman is adjustably connected to a rock-arm 59 (pivoted at 60 on the bracket-arm head 5) by means of a shoulder screw 61 having its threaded end threaded into a block 62 (Fig. 3) slidably mounted in an arcuate slot 63 in the arm 59. The lower end of the rock-arm 59 is pivotally connected, at 64, to one end of a link 65 the other end of which is pivotally connected, at 66, to the upstanding arm 35^a of the above-mentioned three-armed lever 35. The third arm 35^c of the lever 35 (Fig. 4) is pivotally connected, at 67, to a stud 68 projecting horizontally from an upstanding portion 25^a of the collar 25 secured upon the presser-bar 21. The arm 35^c of the lever 35 carries a projecting cylindrical portion 69 which tracks the walls of a guideway 70 formed in a guide-block 71 secured to the bracket-arm head by a screw 72.

From the foregoing, and as shown diagrammatically in Figs. 6 and 7, it will be apparent that rotation of the shafts 6 and 38 will cause the feed-bar 33 to be swung between its full and dotted line positions and will also cause the eccentric 57 and pitman 58 to oscillate the arm 59 about its pivot 60, thereby causing the link 65 to rock the three-armed lever 35 between its full and dotted line positions in Fig. 7.

With the parts of the feeding mechanism in the position shown in Fig. 2 and indicated in full lines in Fig. 7, the eccentric 57, pitman 58, arm 59 and link 65 are in their extreme position toward the front of the machine, the feeding-foot 36 is bearing upon the work and the three-armed lever 35 has been turned clockwise about its fulcrum 34 and has thereby raised the arm 35^c and lifted the presser-bar 21 in opposition to the spring 22. This lifts the presser-foot 23 above the work and places the pressure of the spring 22 on the feed-bar and feeding-foot 36 where it remains during the feeding stroke or, in other words, while the feed-bar 33 and feeding-foot 36 are moved from the position indicated by full lines in Fig. 6 to the position indicated in dotted lines. Rotation of the shafts 6 and 38 and the eccentric 57, 180 degrees from the position illustrated in full lines in Fig. 7, causes the lever 35 to be turned counter-clockwise first about its fulcrum 34, thereby depressing the presser-bar 21 until the presser-foot 23 bears upon the work and thereafter about its fulcrum 69 to lift the feed-bar and the feeding-foot 36, as indicated in dotted lines in Fig. 7. The presser-foot continues to bear upon the work and to hold it while the feed-bar is given its return movement and until the feeding-foot 36 is again depressed upon the work.

From the foregoing, it will be apparent that this invention has provided an improved upper four-motioned feeding mechanism which may be used separately or in conjunction with a lower four-motioned feed mechanism as shown. It will also be apparent that inasmuch as the drive for the improved feeding mechanism comprises continuously rotating elements, as distinguished from oscillatory elements, this construction will produce less vibration and noise than prior constructions and therefore is capable of operating at higher speeds.

Having thus set forth the nature of the invention, what I claim herein is:

1. In a sewing machine having a frame and a rotary drive-shaft journaled in said frame; a work feeding mechanism comprising an upper four-motioned feeding-foot engaging the work at its upper side; a rotary feed-shaft journaled in said frame adjacent and substantially parallel to said drive-shaft; a rotary driving connection between said drive-shaft and said feed-shaft for rotating the latter from the former; a feed-drive eccentric on said feed-shaft; operative connections between said feed-drive eccentric and said feeding-foot to give to the feeding-foot feed and return movement; a feed-lift eccentric on said feed-shaft; and operative connections between said feed-lift eccentric and said feeding-foot to give to the feeding-foot rising and falling movements in timed relation with its feed and return movements.

2. In a sewing machine having a frame and a rotary drive-shaft journaled in said frame; a presser-foot movably mounted on said frame; a work feeding mechanism comprising an upright feed-bar pivotally supported relative to said frame for reciprocatory and oscillatory movements; a feeding-foot carried by the lower end of said feed-bar and engaging the work at its upper side; a rotary feed-shaft journaled in said frame adjacent and substantially parallel to said drive-shaft; a one-to-one rotary driving connection between said drive-shaft and said feed-shaft for rotating the latter from the former; a feed-drive eccentric on said feed-shaft; operative connections between said feed-drive eccentric and said feeding-foot to give to the feeding-foot oscillatory feed and return movements; a second eccentric on said feed-shaft; and operative connections between said second eccentric and said feeding-foot and said presser-foot, alternately to raise and lower said feeding-foot and said presser-foot in timed relation with the feed and return movements of the feeding-foot.

3. In a sewing machine having a frame and a rotary drive-shaft journaled in said frame; a work feeding mechanism comprising a lower four-motioned feed-dog engaging the work at its underside; an upper four-motioned feeding-foot engaging the work at its upper side in opposition to said feed-dog; an upper feed-shaft journaled in said frame adjacent and substantially parallel to said drive-shaft; gears connecting said drive-shaft with said feed-shaft for rotating the latter from the former; a feed-drive eccentric on said feed-shaft; operative connections between said feed-drive eccentric and said feeding-foot to give to the feeding-foot feed and return movements; a feed-lift eccentric on said feed-shaft; and operative connections between said feed-lift eccentric and said feeding-foot to give to the feeding-foot rising and falling movements in timed relation with its feed and return movements.

4. In a sewing machine having a frame including a work-support, an overhanging bracket-arm and a bracket-arm head, and a rotary drive shaft journaled in said bracket-arm; a work feeding mechanism comprising a lower four-motioned feed-dog engaging the work at its underside, an upper four-motioned feeding-foot engaging the work at its upper side in opposition to said feed-dog; an upper feed-shaft journaled in said bracket-arm adjacent and substantially parallel to said drive shaft; a pair of gears connecting said drive-shaft with said feed-shaft for synchronously rotating the latter from the former; a feed-drive eccentric on said feed-shaft; a pitman having one end surrounding said feed-drive eccentric; a segmental arm journaled in said bracket-arm head and connected to the other end of said pitman for oscillation thereby; adjustable link and lever mechanism connecting said segmental arm with said feeding-foot to give to the feeding-foot feed and return movements of variable amplitude; a feed-lift eccentric on said feed-shaft; and operative connections between said feed-lift eccentric and said feeding-foot to give to the feeding-foot rising and falling movements in timed relation with its feed and return movements.

5. In a sewing machine having a frame including a work-support, an overhanging bracket-arm and a bracket-arm head, and a rotary drive-shaft journaled in said bracket-arm; a work feeding and alternating presser mechanism comprising an upright feed-bar pivotally supported relative to said frame for endwise and sidewise movements; a feeding-foot carried by the lower end of said feed-bar and engaging the work at its upper side; a presser-bar reciprocably mounted in said bracket-arm head; a presser-foot secured to the lower end of said presser-bar; an upper feed-shaft journaled in said bracket-arm adjacent and substantially parallel to said drive-shaft; a driving connection between said drive-shaft and said feed-shaft for rotating the latter from the former; a feed-drive eccentric on said feed-shaft; operative connections between said feed-drive eccentric and said feeding-foot to give to the feeding-foot feed and return movements; a feed-lift eccentric on said feed-shaft; a pitman having one end surrounding said feed-lift eccentric; an oscillating lever fulcrumed on said bracket-arm head and adjustably connected to the other end of said pitman; a three-armed lever having two of its arms connected, respectively, to said feed-bar and to said presser-bar; and a link connecting the third arm of said three-armed lever with said oscillatory lever and serving to oscillate said three-armed lever to effect alternate rising and falling movements of said feed-bar and presser-bar under the influence of said feed-lift eccentric.

ANDREW B. CLAYTON.
